The ornamental design for a rechargeable battery, as shown and described.

DESCRIPTION

FIG. 1 is a perspective view of a first embodiment of a rechargeable battery showing my new design;

FIG. 2 is a top plan view thereof;

FIG. 3 is a left side elevational view thereof;

FIG. 4 is a front elevational view thereof;

FIG. 5 is a bottom plan view thereof;

FIG. 6 is a right side elevational view thereof; and

FIG. 7 is a rear elevational view thereof.

FIG. 8 is a perspective view of a second embodiment of a rechargeable battery showing my new design;

FIG. 9 is a top plan view thereof;

FIG. 10 is a left side elevational view thereof;

FIG. 11 is a front elevational view thereof;

FIG. 12 is a bottom plan view thereof;

FIG. 13 is a right side elevational view thereof; and

FIG. 14 is a rear elevational view thereof.

FIG. 15 is a perspective view of a third embodiment of a rechargeable battery showing my new design;

FIG. 16 is a top plan view thereof;

FIG. 17 is a left side elevational view thereof;

FIG. 18 is a front elevational view thereof;

FIG. 19 is a bottom plan view thereof;

FIG. 20 is a right side elevational view thereof; and

FIG. 21 is a rear elevational view thereof.

FIG. 22 is a perspective view of a fourth embodiment of a rechargeable battery showing my new design;

FIG. 23 is a top plan view thereof;

FIG. 24 is a left side elevational view thereof;

FIG. 25 is a front elevational view thereof;

FIG. 26 is a bottom plan view thereof;

FIG. 27 is a right side elevational view thereof; and

FIG. 28 is a rear elevational view thereof.

FIG. 29 is a perspective view of a fifth embodiment of a rechargeable battery showing my new design;

FIG. 30 is a top plan view thereof;
FIG. 31 is a left side elevational view thereof;
FIG. 32 is a front elevational view thereof;
FIG. 33 is a bottom plan view thereof;
FIG. 34 is a right side elevational view thereof; and
FIG. 35 is a rear elevational view thereof.
FIG. 36 is a perspective view of a sixth embodiment of a rechargeable battery showing my new design;
FIG. 37 is a top plan view thereof;
FIG. 38 is a left side elevational view thereof;
FIG. 39 is a front elevational view thereof;
FIG. 40 is a bottom plan view thereof;
FIG. 41 is a right side elevational view thereof; and
FIG. 42 is a rear elevational view thereof.
FIG. 43 is a perspective view of a seventh embodiment of a rechargeable battery showing my new design;
FIG. 44 is a top plan view thereof;
FIG. 45 is a left side elevational view thereof;
FIG. 46 is a front elevational view thereof;
FIG. 47 is a bottom plan view thereof;
FIG. 48 is a right side elevational view thereof; and
FIG. 49 is a rear elevational view thereof.

FIG. 50 is a perspective view of a eighth embodiment of a rechargeable battery showing my new design;
FIG. 51 is a top plan view thereof;
FIG. 52 is a left side elevational view thereof;
FIG. 53 is a front elevational view thereof;
FIG. 54 is a bottom plan view thereof;
FIG. 55 is a right side elevational view thereof; and
FIG. 56 is a rear elevational view thereof.
FIG. 57 is a perspective view of a ninth embodiment of a rechargeable battery showing my new design;
FIG. 58 is a top plan view thereof;
FIG. 59 is a left side elevational view thereof;
FIG. 60 is a front elevational view thereof;
FIG. 61 is a bottom plan view thereof;
FIG. 62 is a right side elevational view thereof; and,
FIG. 63 is a rear elevational view thereof.
The entire contents of design patent application Ser. Nos. 29/088,709 and 29/088,710 both filed May 29, 1998 including drawing descriptions and drawings are incorporated herein by reference.
